UNITED STATES PATENT OFFICE.

EARLE W. MURPHY, OF CAMBRIDGE, MASSACHUSETTS.

BOOK-HOLDER.

SPECIFICATION forming part of Letters Patent No. 694,490, dated March 4, 1902.

Application filed July 1, 1901. Serial No. 66,675. (No model.)

To all whom it may concern:

Be it known that I, EARLE W. MURPHY, a citizen of the United States, residing at Cambridge, in the county of Middlesex and State 5 of Massachusetts, have invented certain new and useful Improvements in Book-Holders; and I do hereby declare the following to be a full, clear, and exact description of the invention, such as will enable others skilled in the 10 art to which it appertains to make and use the same.

This invention relates to devices for holding books open; and it consists in the novel construction and combination of the parts 15 hereinafter fully described and claimed.

In the drawings, Figure 1 is a plan view of the book-holder. Fig. 2 is a side view. Fig. 3 is an end view.

A is a T-shaped frame having a projecting 20 rib along the back of its head to prevent the book from sliding backward off it.

B is a guide-frame which is slidable longitudinally on the longitudinal bar a' of the frame. The guide-frame has guides b arranged crosswise on its under side, and Care 25 cross-bars which are slidable in the guides b parallel with the head of the frame.

D is a clamping-bar pivoted by a bail d to the under side of the front end of the bar a' 30 and foldable underneath it. D' is a cord for securing the clamping-bar.

E are spring-wire pillars which project upwardly from the opposite ends of the cross-bars C. Each pillar E has a spiral spring e 35 and an arm e' . The arm e' has a cranked portion f where it joins onto the spring e , and this cranked portion engages with the main pillar E. The arm e' carries an india-rubber knob or disk g at its free end and has a finger-piece g' for operating it.

The book is opened and is placed with its back upon the bar a' . The cross-bars are slid in the guides b and the frame B is slid on the bar a' , so as to adapt the spring-arms to 40 hold the book in its open position, as shown 45

in Fig. 3, in which the book is indicated in dotted lines. The spring-arms are raised, as shown, and bear downward on the pages of the book.

What I claim is—

1. In a book-holder, the combination, with a T-shaped frame having a longitudinal bar, of a guide-frame slidable longitudinally on the said bar and provided with two parallel guides on the under side thereof, cross-bars 55 slidable in the said guides, and pillars provided with spring-arms and projecting upwardly from the end portions of the said cross-bars, substantially as set forth.

2. In a book-holder, the combination, with a T-shaped frame having a longitudinal bar, of a guide-frame slidable longitudinally on the said bar and provided with two parallel guides on the under side thereof, cross-bars 65 slidable in the said guides, and spring-pillars 65 projecting upwardly from the end portions of the said cross-bars, each said spring-pillar being provided with a spiral spring connected to its top portion, a cranked portion projecting from the inner coil of the spring cross-wise of the main portion of the pillar, an arm 70 projecting from the said cranked portion, and a knob at the free end of the said arm, substantially as set forth.

3. The combination, with a T-shaped frame 75 having a longitudinal bar, of a guide-frame slidable longitudinally on the said bar and provided with two parallel guides on its under side, cross-bars slidable in the said guides and provided with spring-arms for bearing on 80 the pages of the book, and means for clamping the two said cross-bars in their guides, substantially as set forth.

In testimony whereof I affix my signature in presence of two witnesses.

EARLE W. MURPHY.

Witnesses:

ALICE J. MURRAY,
FREDK. K. DAGGETT.
